ATTORNEY.

UNITED STATES PATENT OFFICE

2,008,615

WINDOW CLEANER

Kenneth S. Rogers, Niles Township, Berrien County, Mich., assignor to Squee-Wash Mfg. Co., Niles, Mich.

Application May 1, 1935, Serial No. 19,185

5 Claims. (Cl. 15—121)

The invention relates to window cleaners, and particularly to a cleaner including a water absorbing member and a squeegee.

The primary object of the invention is to provide a device of this character which may be inexpensively manufactured and assembled.

A further object is to provide a device of this character formed of a plurality of parts which cooperate and fit together to be operatively interconnected in stationary relation by a single securing member.

Other objects will be apparent from the description and appended claims.

In the drawing:

15 Figure 1 is an end view of the device.

Figure 2 is a fragmentary side view of the device.

Figure 3 is a fragmentary sectional view of the device taken on line 3—3 of Figure 2.

20 Referring to the drawing, which illustrates the preferred embodiment of the invention, the numeral 10 designates an elongated handle member which has a substantially V-shaped groove 11 cut in one end thereof and extending diametrically thereof.

25 A holder 12 for a rubber sponge or other water absorbing and applying member 13 is adapted to be mounted on the grooved end of the handle. The member 12 is preferably formed of sheet metal and comprises an elongated channel having a base portion 14, side portions 15 extending from said base in converging relation and each terminating in an outwardly flaring flange 16. The rubber sponge 13 is held in said channel member 12 by the restricted throat between the opposite walls thereof at the junction of sides 15 with their respective flanges 16 in spaced relation to base 14, and the flanges 16 serve to support the sponge adjacent said restricted throat to prevent cutting and tearing of the sponge while in use.

30 A holder 17 for a rubber squeegee strip 18 is adapted to be secured to the sponge holder 12. Holder 17 is preferably formed of integral sheet metal construction and comprises an elongated base portion 19 from which angularly extends a body plate or portion 20 which is outwardly return bent at 21 in spaced relation to base portion 19 and again outwardly return bent at 22 to provide a pair of spaced jaws 23 for gripping the squeegee strip 18, and for holding the same in parallel relation to the base 19.

35 In the assembly of the parts, the sponge holder 12 is mounted in the groove 11 of handle 10 with a portion of its base 14 and of one side wall 15 preferably lying in face contacting engage-

ment with the walls of said groove and its opposite ends equally spaced from said handles. In this arrangement, the sponge is held at an angle and at one side of the handle, and the side wall 15 of holder 12 opposite that mounted in the groove 11 is positioned in substantially perpendicular relation to the axis of the handle and spaced from the handle. The squeegee holder 17 is then applied to this assembly with its base portion 19 in face contacting engagement with said last-named perpendicular side 15 of holder 12, the edge of said portion 19 being positioned adjacent to or in contacting engagement with the flange 16 of said side 15. In this arrangement the squeegee holder is positioned in angular relation to the sponge holder and the handle whereby said squeegee is disposed in parallel relation to said sponge but spaced therefrom and on the opposite side of said handle. A single securing member, preferably wood screw 24, may 20 then be used to secure the parts to said handle, said screw passing through portion 19 of squeegee holder 17, one side 15 of the sponge holder, the sponge, the opposite corner of the sponge holder, and axially into said handle 10.

25 It will thus be seen that the handle groove 11 serves to position the sponge holder in stationary relation to said handle, in cooperation with said screw; and that the edge bearing engagement of base 19 of holder 17 with flange 16 of holder 12, in cooperation with said screw, serves to lock said holders in stationary operative relation. It will also be seen that either the squeegee or the sponge may readily be replaced by simply removing the screw 24, thereby disassembling the parts, 30 reassembling the parts including the new part, and again applying screw 24.

35 I claim:—

40 1. A window cleaner comprising a cleaning element holder of channel section including a base and converging sides terminating in diverging flanges, a second cleaning element holder including an angularly bent base flange, an elongated handle having a groove formed in one end thereof, said groove receiving said first mentioned holder at a corner thereof between the base and one side thereof whereby the other side thereof is positioned substantially perpendicular to said handle, the base flange of said second cleaning element holder being disposed in face contacting engagement with the last named side of said first mentioned holder with its edge engaging the flange of said side, and a securing member passing 45 through said base flange, said first mentioned holder 50 being disposed in face contacting engagement with the last named side of said first mentioned holder with its edge engaging the flange of said side, and a securing member passing through said base flange, said first mentioned holder 55

er, and into said handle to operatively secure said parts in stationary relation.

5. A window cleaner comprising an elongated cleaning element holder of channel section, an elongated handle having a groove across one end thereof receiving the central portion and one side of said holder with its longitudinal axis and central plane disposed at an angle to the axis of the handle, a wiper holder having a base portion disposed in face contacting engagement with the other side of said first named holder, a securing member extending through said base portion, said first named holder, and into said handle, and means formed integrally with said first named holder and engaged by said wiper holder for locking said holders against relative movement when secured to said handle.
10. A cleaning device comprising a handle having a groove extending across one face thereof, a channel shaped holder for the reception of a cleaning element, the adjacent spaced side walls of the holder forming an opening at an angle to the face of the handle, one side of said holder being disposed in the groove of the handle in a position whereby the side wall of the holder within the groove will be rigidly held by the handle,
15. A device as set forth in claim 4 including a second carrier mounted on the last named wall and secured thereto by the securing member extending therethrough.

the other side wall of said holder being above and spaced from the handle member and securing means extending through the last named side of the holder and through the other side of the holder and into the handle member and forming means whereby the cleaning element is gripped within the holder member and holder fixed to the handle.

4. A cleaning device comprising a handle having a groove formed in one face thereof, a carrier 10 for a cleaning element, said carrier comprising a base and opposed side walls extending angularly inwardly from the base, one corner of said carrier including parts of the base and one side wall being seated in said groove to position the 15 opposite side wall of the carrier in substantial parallelism with the grooved face of said handle and a securing member extending through the last named wall and the seated corner of said carrier and into said handle and serving to press 20 said carrier walls inwardly.

5. A device as set forth in claim 4 including a second carrier mounted on the last named wall and secured thereto by the securing member extending therethrough.

KENNETH S. ROGERS.
